UNITED STATES PATENT OFFICE.

EARL MARVIN PLUMMER, OF CHICAGO, ILLINOIS.

SPARK-PLUG TESTING AND INDICATING DEVICE.

Application filed March 17, 1921. Serial No. 453,107.

To all whom it may concern:

Be it known that I, EARL M. PLUMMER, a citizen of the United States, and a resident of Chicago, in the county of Cook and State 5 of Illinois, have invented certain new and useful Improvements in Spark-Plug Testing and Indicating Devices, of which the following is a specification.

This invention relates to a spark plug 10 testing and indicating device.

The object of the invention is to provide such a device, whereby the functioning or condition of each of the spark plugs of an engine may be continuously indicated. It 15 is also an object of the invention that in case any spark plug becomes fouled or otherwise inoperative an alarm will indicate such condition.

The invention is particularly adapted for 20 use in connection with an automobile and so illustrated in the accompanying drawings, in which:

Figure 1 is a top plan view of the housing and supporting means for the spark gap 25 terminals,

Figure 2 is an end elevation of the box or housing shown in Figure 1,

Figure 3 is a transverse section of the box or housing shown in Figure 1,

Figure 4 is a diagrammatic view illustrating the preferred embodiment of my invention, and

Figure 5 is a detailed view of the auxiliary spark terminals.

Referring to Figure 4 more particularly, 35 10 indicates a battery which is grounded on its one side as at 11. The other side of this battery is led to one end of the primary winding of the induction coil 12, and the 40 other side of said coil is grounded as indicated at 13. One side of the secondary of the coil 12 is connected in the usual manner to the distributing box 14, and its other side grounded as at 14'. The distributing box 45 has extending therefrom a lead 15 for each of the spark plugs 16 which in this instance are four in number.

Referring to Figure 1 the box or housing 50 generally indicated by the reference letter A comprises a rear wall 17, the top and bottom walls 18 and the front wall 19 which is preferably of glass as shown. Mounted within the box is a substantially U-shaped member 20. The horizontal portions of 55 this U-shaped member are provided with threaded openings in equally spaced rela-

tion and adapted to receive the threaded terminal posts 21. Each post is provided with a knurled nut, 22, so that the same may be locked in adjusted position. Also each 60 of these posts has a slotted head as indicated at 23 for accommodating a screw driver in adjustment. These terminal posts are provided in pairs as shown and each pair represents an opening or spark gap in the circuit of each spark plug 16. As illustrated in Figure 4 the circuit of each spark plug comprises a lead 15 which extends from the distributing box 14 to a terminal of one of the pairs of the spark gap terminals 22 and 70 also the lead 24 which connects the other terminal of said pair with its respective spark plug 16. Each spark plug is grounded as at 25 to the frame of the engine in the usual manner, which completes the circuit to 75 the secondary of the induction coil 12.

An auxiliary spark terminal is provided for each pair of terminals 22. This auxiliary spark terminal is particularly illustrated in Figure 5, and comprises an elongated portion 25 on each side of which there is formed an angular projection 26. The elongated portion 26 is also provided with an opening adapted to receive the terminal posts 21. These auxiliary spark terminals 80 are mounted as shown in Figure 1 and held in position by the knurled nuts 22. The forward end may be bent downwardly as at 28 to more securely hold the same in position. As is obvious, the end auxiliary spark 85 terminals need only have a projection 26 on the inner side thereof.

It also may here be pointed out that the top or cover of the box A may be removable and secured in position by means of screws 95 or the like as indicated at 29; and that the rear wall 17 may be suitably secured to the instrument board of the automobile.

In the operation of the present apparatus, if the spark plugs 16 are properly functioning the passage of the spark between the pairs of terminals 21 will be intermittent and regular, but in case a spark plug circuit is opened or otherwise offers a great resistance to the passage of the current, the jumping of the spark between the pair of terminals 21 for the spark plug which was out of order would cease, and instead, a spark would jump between the auxiliary terminals of this faulty spark plug circuit and the adjacent spark plug circuit, the current from thence going to the ground through a spark 100 105 110

plug which is in good condition. A spark jumping between adjacent auxiliary spark terminals would produce a cracking sound of an irregular character and attract the attention of the driver or operator of the automobile and hence he would immediately become aware that the defective spark plug needed attention. In this manner the particular spark plug which is out of order is indicated to the driver.

- the same could be equally used with any type of engine serving any purpose. 20
- I claim:
1. In a device of the character described, a member made of insulating material, a plurality of spark terminals carried by said member and arranged in pairs, and auxiliary 25 spark points carried by said terminals and adapted to establish spark gaps between adjacent terminals.
  2. In an ignition apparatus, a pair of spaced conductors, each conductor being 30 adapted to be included in a high potential circuit of the ignition apparatus, and a projection extending from each conductor adapted to establish a spark gap between the free ends thereof.

EARL MARVIN PLUMMER.

As long as the passage of the sparks between the spark gap created by each pair of spark terminals 21 is regular and intermittent, the driver will know that the spark plugs are functioning properly.

While I have shown and described this invention when used in connection with an automobile engine it is to be understood that
